Carpets

No. 11,691

March 16, 1880

UNITED STATES PATENT OFFICE.

THOMAS J. STEARNS, OF BOSTON, MASSACHUSETTS, ASSIGNOR TO ROXBURY CARPET COMPANY, OF SAME PLACE.

DESIGN FOR CARPETS.

SPECIFICATION forming part of Design No. 11,691, dated March 16, 1880.

Application filed January 30, 1880. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration.

The design is composed of blossoms A, each composed of regular petals, sinuous branches or vines B, supporting the blossoms A, and leaves and buds supported by the vines and forming an intricate chintz-work, all arranged on a light or contrasting ground. The leaves 15 all have the same general form, and the sinuous vines have the effect of extending almost continuously throughout the length of the piece.

These features—viz., the uniform leaves and the continuous sinuous vines—distinguish the 20 design from that shown in my patent No. 11,147, dated April 18, 1879, the last-named design being destitute of vines, and showing several radically-different forms of leaves.

I claim—

The design for a carpet, comprising the sinuous vines B, with leaves, blossoms, and buds, substantially as shown and described.

In testimony whereof I have signed my name to this specification, in the presence of two 30 subscribing witnesses, this 23d day of January, A. D. 1880.

THOMAS J. STEARNS.

Witnesses:

W. SCHMIDT,
C. F. BROWN.
